UNITED STATES PATENT OFFICE.

AUGUST W. L. HARTBAUER, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

HOOD PANEL-CASTING.

1,078,278.

Specification of Letters Patent.

Patented Nov. 11, 1913.

Application filed August 14, 1912. Serial No. 715,095.

To all whom it may concern:

Be it known that I, AUGUST W. L. HARTBAUER, residing at 915 Olive street, St. Louis, Missouri, and being a citizen of the United States, have invented certain new and useful Improvements in Hood Panel-Castings, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is an end elevation of one-half of the upper portion of a car showing the upper deck roof sheet partly broken away. Fig. 2 is a fragmentary view of a portion of the device shown in Fig. 1, with the panel casting also removed. Fig. 3 is a perspective view looking down upon the hood and adjacent parts, the upper deck roof sheet being removed. Fig. 4 is a perspective view showing the lower deck roof sheet lapping the fascia and end plate. Fig. 5 is a view similar to Fig. 4 with parts broken away to show the connection of the deck sill and platform end carline. Fig. 6 is a vertical, transverse, sectional view taken on a plane indicated by the line 6—6, looking in the direction indicated by the arrows, and Fig. 7 is a horizontal, transverse, sectional view taken through the hood panel casting at the carline and taken on the plane indicated by the line 7—7, looking in the direction indicated by the arrows.

My invention relates to a vestibule hood for double deck or monitor type of cars, and particularly relates to the hood panel casting and its connection with its co-operating members.

A particular object of the invention is to provide a firm, neat connection between the hood panel casting and co-acting members, so that water falling upon the panel casting or any of the other members will be readily drained off of the same without the possibility of the water creeping within the hood through the riveted connections.

A further object of this invention is to provide a construction of the character above

described in which the several parts are neatly and securely fastened one to the other.

Described more in detail I have shown a hood construction particularly adapted for monitor or double deck types of hood and showing a conventional form of main carline A, in the present instance shown to be an inverted square U-shaped angle T-shaped in cross section fastened by means of the usual castings to the deck sills B, which deck sills have their outer ends supported above the platform end roof carline C by means of a spacing and supporting member D, which member D is shown to be in the form of a three-sided box having inclined outer edges adapted to fit beneath the lower deck hood roof sheet, hereinafter described.

Depending from the front vertical flange of the carline C and riveted thereto is the end plate E, the opposite transverse sides of which are riveted to the side fascia plates F, which fascia plate has its upper edge overlapped by and riveted to a rounded depending flange g of the lower deck roof sheet G from a point spaced from the adjacent carline C to a correspondingly spaced point at the opposite end of the car.

The space from the end of the plate G to the end plate E is covered by a lower deck hood roof sheet H, which, as shown, is a single pressed sheeting extending in an arch downwardly and outwardly in both a transverse and longitudinal direction and having depending flanges h and h² overlapping and riveted respectively to the outer upper side of the fascia plate F and end plate E. The upper edge of the plates G and H are curved upwardly to form a vertically extending attaching flange 6, by means of which the plate G is fastened to the carline A and hood panel casting J, hereinafter described.

As shown more particularly in Fig. 4, the upper edge 7 of the flange 6 on the plate H is uniformly spaced from the line where the flange 6 rounds off into the top of the plate H, except that adjacent the meeting of the plate H with the carline C, the upper edge is horizontally disposed, thereby forming a vertically disposed side facing 9, substantially triangular in shape, disposed at right angles to the plane of which and inclined inwardly and upwardly from the rear depending flange h² is a rear facing 10, the facings 9 and 10 meeting to form an inclined

corner or angle 11 to fit the correspondingly formed lower inside corner of the hood panel casting J.

Projecting vertically from the rounded angle formed by the plates G and H and the flange 6 and extending between the carline A and the end plate E is the hood panel casting J, particularly forming the subject matter of this invention. This casting is shown to comprise a flat vertical sheet 15 semilunar or claw shape in side elevation, (see Fig. 3), the lower end of which fits flush against the facing 9. Projected inwardly from and integral with the top edge 16 of which and extending from the front face of the carline A to and overlapping the flange h^2 is a curved hood roof plate 12, the lower end of which has a flat face 13, conforming to and resting on the facing 10 and an extension 14 depending below the end of the sheet 15 and fastened to the roof sheet H, end plate E and carline C by rivets 16. The lower outlining edge of the plate 15 rests on the top of the sheets G and H and is fastened to the upstanding flanges 6 by means of rivets 17, and the rear vertical edge 18 is reduced in thickness and fastened to the outside of the vertical leg of the carline A by rivets 19. The upper deck roof sheet (not shown) is correspondingly reduced where it laps the front face of the carline and these reduced portions are fastened to the carline A by means of the splice plate 23, the parts being held by the parallel rows of rivets 19 and 24, respectively, passing through the plate 15 and upper deck roof sheet and through the splice plate 23 and flanges of the carline A. In order to form a connection with the upper deck roof sheets, the upper rear edge of the hood panel casting may be stepped as shown at 22.

By the construction above outlined, it will be seen that a water-tight, neat and firm connection is formed between the hood panel casting J, the lower deck hood roof sheet H and the lower deck roof sheet G. Any water falling on panel casting J runs down the sheet 15 off the side of the plates H and G to the outside of the overlapping connection between these members and the fascia plate F. Further the hood roof plate 12 forms a neat overlapping joint with the end plate E and rear flange h^2 of the lower deck hood roof sheet H, permitting water to flow off the hood in this direction.

If it should be desired to brace the plate 15 a downwardly and forwardly curved angle or rib 20 may be extended from the outer face of the plate 15 spaced downwardly from the curved angle between the plate 15 and roof hood plate 12; this angle, it will be noted, also affording a water drip at the side of the hood tending to direct the water off the end of the hood.

Extending longitudinally over and fitted to the configuration of the top of the carline A and projecting transversely over a portion of the roof plate 12, as shown in Fig. 1, is an upper deck roof sheet K, the lower forward end of which is fastened to the end plate E by means of rivets 21, the end rivet of the series of which may be one of the rivets 16 passing through the roof hood 12.

In order to space the lower forward end of the sheet K from the end plate E, a filler strip L extends across the face of the plate E, and is disposed between the said plate and the sheet K, and between the panel casting in which position it is held by the rivets 21. This filler strip is of a thickness equal to the thickness of the extension 14, so as to form a water-tight connection between the sheet K and end plate E, and at the same time will bring the sheet K in a plane with the outer face of the hood sheet 12 and filler L. By this construction it will be seen that water falling on the roof sheet K will fall off the sides, as hereinbefore described, or will fall off the rear of the sheet K, the positioning of the filler L above the lower edge of the sheet forming a water drip which will prevent the water from creeping back to the end plate E or to the inside of the hood.

While the hood panel member J has been described as a casting, and will in all probability be formed in cast metal, it is, of course, to be understood that this member may be made from rolled metal with the angle 20 riveted, or otherwise fastened thereto, or in which the plate 15 and hood panel roof 12 may be separate members suitably welded, riveted or otherwise fastened together.

What I claim is—

1. The combination of an end plate, a panel casting overlapping and affixed to the outer face of said end plate, a filler mounted on the outer face of said end plate having its outer surface flush with the outer surface of said casting, and an upper deck roof sheet affixed to said casting and filler.

2. The combination of a fascia plate and an end plate, a single curved lower deck hood roof sheet overlapping said plates and affixed thereto, a hood panel casting overlapping said roof sheet, an upper deck roof sheet overlapping said panel and means fastening said members together.

3. The combination of a lower deck roof sheet and a lower deck hood roof sheet, a single panel casting uniting and overlapping said roof sheets.

4. The combination of a lower deck roof sheet and a lower deck hood roof sheet, a single panel casting uniting said roof sheets in position and a bracing rib or angle reinforcing said panel.

5. The combination with a fascia plate and an end plate, of a single curved lower deck hood roof sheet overlapping said plates and affixed thereto, and having an 5 upstanding flange with a side and rear face adapted to be lapped by a hood panel casting.

6. As an article of manufacture, a unitary hood panel casting, consisting of a flat 10 vertical sheet semilunar in shape and a curved hood roof plate angularly disposed

relative to the sheet having a flat lower face depending below the sheet whereby the same may be fastened to the outer face of an end plate.

In witness whereof I have hereunto set my hand in the presence of two witnesses.

AUGUST W. L. HARTBAUER.
